UNITED STATES PATENT OFFICE.

CHARLES W. HARROLD, OF CLEVELAND, OHIO, ASSIGNOR TO THE HARRIS AUTOMATIC PRESS COMPANY, OF CLEVELAND, OHIO, A CORPORATION OF OHIO.

PRINTING PRESS.

Application filed April 1, 1922. Serial No. 548,712.

To all whom it may concern:

Be it known that I, CHARLES W. HARROLD, a citizen of the United States, and a resident of the city of Cleveland, in the county 5 of Cuyahoga and State of Ohio, have invented certain new and useful Improvements in Printing Presses, of which the following is a specification, reference being made to the accompanying drawings, forming a part 10 thereof.

My invention relates to printing presses and is preferably embodied in a rotary press in which there are improved devices for separating the printing or other coacting members forming a printing couple; the objects 15 of my invention are, among other things, to provide in a rotary press improved devices not only for separating the printing members, but also for throwing off the inking rolls in such press, the two throw-offs being positively actuated from the same source of power in the further movement of the press, and sequentially and variably timed relatively to each other. By my improved mechanism the impression throw-off positions a member in the inker throw-off mechanism thereafter to be directly actuated by means operated by further movement of the press, which means may be adjusted to 20 alter the timed sequence of the two throw-offs as the best practice may require. By my improvement the impression throw-off may advantageously occur at a fixed point when the gaps of the several cylinders are 25 adjacent one another, and the inker rolls are subsequently raised when about to pass over the opening in the form or plate-cylinder, both throw-offs being positively operated by the continued rotation of the impression-cylinder and deriving their actuation 30 from a non-shiftable member in the press.

Furthermore I have embodied in my improved press automatic means, controlled by 35 the interruption or absence of stock in the feed supply, to throw off the inking mechanism independently of the throw-off of the printing members at the same period in the cycle of operation as if the printing members 40 were also connected to be automatically actuated by the feeder trip. Such automatic devices are also combined with manual means whereby the operator may position a member in the inker throw-off which will 45 thereafter automatically throw-off the in-

king rolls at a predetermined point in the continued movement of the press.

My improved printing-press also embodies other features of novelty and usefulness whereby the operating mechanisms are simplified and made more effective and otherwise better adapted for use, all of which will be hereinafter set forth and then particularly pointed out in the appended 60 claims.

The drawings illustrate my invention in its preferred embodiment in a three cylinder "off-set" press, the same serving to fully explain the nature of my improvement, which is not restricted, however, to any 70 particular type of rotary press, since my invention may also be embodied in a two cylinder press with the same advantages and results.

Of the drawings, Fig. 1 is a side elevation 75 showing the throw-off mechanism in normal position as applied to an "off-set" press;

Fig. 2 is a view similar to Fig. 1 showing the impression throw-off with the three cylinders separated, and the inker mechanism set to throw off the inking rolls; 80

Fig. 3 is an enlarged detail view showing a form of sheet detector mechanism that may be used in connection with the trip for the cylinders and also for the inker rolls; 85

Fig. 4 is an enlarged detail view of the latch embodied in the inker throw-off mechanism;

Fig. 5 is a fragmentary view showing the inker throw-off as having operated to raise 90 the inking rolls from the form or plate-cylinder;

Fig. 6 is a fragmentary view showing a modified form of my improvement with devices to set the inker throw-off mechanism, the parts being shown in normal position; 95 and

Fig. 7 is a fragmentary view showing the modified form of the inker throw-off as having operated to set the arm which actuates the inker throw-off. 100

Similar numerals refer to similar parts throughout the several figures.

Referring more particularly to Fig. 1, the frame 8 supports the bearings for the form-cylinder 9, the transfer or blanket-cylinder 10 and the impression-cylinder 11, these cylinders being mounted on the shafts 12, 13 and 14 respectively. The cylinders are so constructed and arranged in the frame 8 that 105 110

the transfer-cylinder 10 forms a printing couple with the impression-cylinder 11, after receiving its design from the form-cylinder 9. The respective cylinders have each fastened thereto suitable gears the pitch-diameters of which coincide with the peripheries of the respective cylinders. These gears intermesh and form the driving mechanism to secure the proper rotation of the cylinders 41, the length of this end 49 being regulated by adjusting units 50. Pivotedly secured to the stud 51 is the depending arm 52 carrying the shoulder 53 faced with a hardened plate and adapted to be engaged by the end 49 of the rod 48 as shown in Fig. 2. Adjacent the stud 51 is the stud 54 upon which is pivotally mounted the bell-crank lever 55 which carries the shoulder 56 of similar construction and function as the shoulder 53, Fig. 1 showing the shoulder 56 in operative alignment with the rod-end 49 after having been engaged thereby. The lower arm 57 of the lever 55 is connected by the link 58 to the arm 52. The arms 52 and 57 carry adjustable pins 59 and 60 respectively adapted to engage with the stop-pin 61 to limit the movements of the arms 52 and 57 respectively as shown in Figs. 1 and 2. The upper arm of the bell-crank lever 55 is the toggle lever 26 pinned at 27 to the toggle lever 25. It will be noted that the arms 52 and 57 as they are rocked on their respective studs 51 and 54 are maintained in substantial parallelism by the link 58. The toggle lever 18 and toggle arm 20 of the bell-lever 22 form a compound toggle connection with the arms 17 for the eccentric bearings 15 of the transfer-cylinder 10, whereby this cylinder 10 is separated from both form-cylinder 9 and impression-cylinder 11, and the impression throw-off, when the rod-end 49 is shifted to the right and pressed down on the shoulder 53 by the cam 32 as shown in Fig. 2 which movement causes the arm 52 to swing to the right. The impression is restored when the rod-end 49 is swung to the left by the spring 47 and pressed down thereafter on the shoulder 56 by the action of the cam 32 to swing the arm 57 to the left to break the toggle levers 25 and 26 thereby moving the eccentric bearings 15 to the left to restore the transfer-cylinder 10 to printing relation.

The shaft 13 carrying the transfer-cylinder 10 is mounted at both ends in the eccentric bearings 15, which, in turn, are mounted in the journals 16 secured in the frame 8. The bearings 15 have arms 17 projecting from flanges on the outside of the frame 8 as shown on one side thereof. The adjustable toggle lever 18 is pivotally connected at 19 to the toggle arm 20 of the bell-crank lever 22 mounted on the stub-shaft 23 secured to the frame. The arm 24 of the lever 22 pivotally carries the toggle lever 25 connected with the toggle lever 26 by the pin 27 which projects inwardly therefrom toward the frame 8. The shaft 14 for the impression-cylinder 11 is mounted at both ends in eccentric bearings (not shown) journaled in the frame 8 which bearings have arms 28 connected by link 29 to the throw-off bracket 30 operated by treadle 31 whereby the impression-cylinder 11 may be thrown off or on with respect to the transfer-cylinder 10 at will.

The automatic throw-off and throw-on mechanism for the transfer-cylinder 10 will now be described: The impression-cylinder shaft 14 carries the cam 32 which engages the roller 33 on the lever-arm 34 pivoted on the stud 35 in the bracket 36 secured to the frame 8. The lug 37 on the lever-arm 34 slidably carries the rod 38 about which is coiled the spring 39 which acts to maintain the roller 33 in engagement with the periphery of the cam 32. The lower end of the rod 38 is pivotally secured to the bracket 36 by the pin 40. The lever-arm 34 also carries the depending bracket 41 which is pivotally connected by the link 42 to the depending arm 43 projecting downwardly from the bell-crank lever 44 pivoted to the stud 35. The arm 43 also carries the lug 45 through which the rod 46 passes with its inner end pivotally secured to the pin 40 with the spring 47 coiled about the rod 46 normally to hold the arm 43 in its left-hand position shown in Fig. 1. The bracket 41 slidably supports the rod 48 with its lower end 49 projecting below the bracket

the position of the throw-off and throw-on mechanism heretofore described to throw the transfer-cylinder 10 off impression. The hand-lever 69 is connected to the shaft 63 to restore impression and reset the latch-trip mechanism now to be described.

The shaft 63 is held in the position shown in Fig. 1 by the latch 70 pivoted on the shaft 71 journalled in the frame 8 and extending across the feed-table 62 as shown in Fig. 3. The latch 70 engages with the notch 72 in the collar 73 mounted on the shaft 63 as shown in Fig. 3. Preferably this latch 70 is released automatically through trip mechanism on the feeder: The feed-table 62 supports the stock 74 that is being fed to the press. Extending transversely above the feed-table 62 and journalled in uprights at the sides thereof is the shaft 75 which carries the arm 76 (Fig. 1) connected by the rod 77 to the impression-cylinder shaft 14 by means of the pin 78 so as to impart to the shaft 75 an oscillating movement. 79, 79 are grooved collars rigidly secured to the shaft 75. Adjacent each grooved collar 79 is the disk 80 affixed to the inner end of the tubular shaft 81 which is loosely sleeved on, and encloses a portion of, the shaft 75, as shown in Fig. 3. The tubular shaft 81 carries the arm 82 having a projecting lug 83 which engages with the arm 84 secured to the shaft 71. The trip-lever 85 is pivoted at 86 between the parallel sides of the grooved collars 79, so that its longer and heavier arm is held from falling into the aperture 87 cut in the top of the feed-table 62 by the interposition of the stock 74 as shown in Figs. 1 and 3. The opposite end of the lever 85 is T-shaped to form the laterally-ending tooth 88; in the peripheries of the collars 79 and also of the disk 80 are formed cut-outs 89 and 90 respectively. Ordinarily the tooth 88 rests against, or is in proximity to, the periphery of the disk 80; it can engage with the cut-out 89 of the collars 79 only when it can fall into the cut-out 90 of the disk 80. When this occurs the disk 80 with its tubular shaft 81, which are normally at rest, are locked to and turn with the oscillating shaft 75. The entrance of this tooth 88 into locking engagement with the disk 80 will occur upon the failure or interruption in the feed supply. When the stock 74 is in proper position, as shown in Figs. 1 and 3, the curved longer arm of the trip-lever 85 will engage therewith and will be prevented from lowering into the aperture 87, and from turning sufficiently to interlock with the disk 80. If the stock 74 should, at any time, be interrupted or absent, the longer arm of the trip-lever 85 will fall of its own weight into the aperture 87, thereby causing the tooth 88 to interlock with the cut-out 90 in the disk 80. Thus the tubular shaft 81 will be caused to oscillate with the shaft 75 to lift the arm 82 to release the latch 70 engaging the notch 72 in the collar 73 on the shaft 63. Through this movement of the herein described mechanisms the shaft 63 is partially rotated by the spring 64 to throw-off the impression by separating the transfer-cylinder 10 from the form-cylinder 9 and impression-cylinder 11 as shown in Fig. 2 all controlled automatically by the stock.

The inking rolls 91 are mounted on the transverse shafts 92 carried in slotted bearings 93 formed in the frame 8 as shown in Fig. 1. Each inking roll 91 has a cylindrical bearing 94 concentric with its shaft 92 adapted to be engaged by rollers 95 mounted on two rock-arms 96 and 97 pivotally secured to studs 98 and 99 respectively. The inner ends of the arms 96 and 97 are operatively connected by the links 100 and 101 respectively to the bell-crank lever 102 pinned at 103 to the frame 8. The arm 104 of the lever 102 is connected by the curved rod 105 to the rock-lever 106 mounted on the stud 107. The vertical arm 108 from the lever 106 is connected by the link 109 to the rock-arm 110 which is actuated by the hand-lever 111 to raise the inking rolls 91 from the form-cylinder 9 when the arm 108 is swung to the left as shown in Fig. 5 which movement depresses the rod 105, thereby swinging the arms 96 and 97 upwardly to throw the inking rolls 91 out of engagement with the form-cylinder 9.

The rocking movement of the rock-lever 106 to throw off the inking rolls 91 in timed relation with the impression throw-off is accomplished by the following mechanism: The bell-crank lever 112 is mounted on the stud 113 and its upper arm 114 has the curved face 115 formed in its extremity in which is cut the notch 116 which is engaged by the spring-pressed latch-pin 117 carried by the socket 118 secured to the stud 119 as shown in Fig. 4. The spring 120 within socket 118 and coiled about the screw-threaded rear end 121 of the latch pin 117 to bear upon the base of the latch-pin 117 normally presses the latter outwardly to engage with the notch 116 to hold the bell-crank lever 112 in its upper position shown in Fig. 1. Pivoted to the arm 114 is the upright arm 122 having the recessed shoulder 123 formed on one side of its upper end to engage with the projecting pin 124 carried by the arm 125 of the rock-lever 106 when the bell-crank lever 112 is drawn downwardly as shown in Figs. 2 and 5. Pivoted to the arm 122 is the laterally extending rod 126 the forward end of which extends through the arm 127 projecting at right angles from the arm 114 with its tip extending outwardly and carrying the adjusting nuts 128 pivotally secured to the frame. Between the arm 127 and the nuts 128 is fastened the tension spring 129 coiled

about the rod 126 which tends normally to raise the bell-crank lever 112 from its lowered Fig. 2 position into the position shown in Fig. 1 so that the latch-pin 117 will 5 engage the notch 116 to hold the lever 112 as shown in Fig. 4. Between the arm 127 and the adjustable nuts 130 carried by the rod 126 is the compression spring 131 coiled about the rod 126 to force the arm 122 into 10 engagement with the pin 124 when the bell-crank lever 112 is drawn downwardly with the latch-pin 117 released as shown in Fig. 2.

The arm 114 is unlatched and the bell-crank lever 112 drawn downwardly to set 15 the inker throw-off mechanism in position for operation by the following device: Pivotedly secured to the arm 114 is the depending arm 132 having the inclined notch 133 formed in one side which engages with 20 the projecting pin 27 connecting the toggle levers 25 and 26 as shown in Fig. 1. The arm 132 is constantly under tension from the spring 134 connecting same to the stud 135 secured to the frame 8. A stop-pin 136 25 is fixed in the frame 8 so that when the toggle levers 25 and 26 are straightened as shown in Fig. 2, the notch 133 will be unlatched from the pin 27 when the toggle movement is about half completed. When 30 this toggle is fully straightened as shown in Figs. 2 and 5, the pin 27 is out of the path of movement of the arm 132 which may then be drawn upwardly when the bell-crank lever 112 is swung upwardly in order to 35 throw off the inking mechanism and reset the latch-pin 117.

This bell-crank lever 112 is swung upwardly by the following mechanism: The arm 137 of the lever 112 carries the cam-roller 138 which is adapted to be engaged by the cam 139 which is adjustably mounted (by means not shown) on the impression-cylinder shaft 14 so that the action of this cam 139 may be variably adjusted in predetermined 40 sequence to action of the impression-throw-off cam 32 to change the timing of the two throw-off movements as may be desired. In 45 the present embodiment this inker-throw-off cam 139 does not operate until about two thirds of a revolution of the cylinder 11 after the impression has been tripped by the cam 32 as shown in Figs. 2 and 5.

The operation of the hereinbefore described mechanism is substantially as follows:

Whenever the stock 74 is interrupted or is absent from the feed-table 62, the trip-lever 85 acts to release the spring-impelled shaft 63, the bracket 41 with the rod-end 49 50 swinging to the right as shown in Fig. 2. As this movement takes place the cam 32 is revolved from the position shown in Fig. 1 to that in Fig. 2 thereby forcing the rod-end 49 downwardly on the shoulder 53 which 55 swings the arm 57 to the right until the pin

60 engages with the stop 61. This movement simultaneously straightens the toggle levers 25 and 26 to shift the eccentric bearings 15 for the transfer-cylinder 10 to separate the latter from both the form-cylinder 70 9 and the impression-cylinder 11 as shown in Fig. 2. As the toggle levers 25 and 26 are being straightened, the projecting pin 27 engages with the notch 133 of the depending arm 132 to draw downwardly the bell-crank lever 112 which simultaneously releases the latch-pin 117 and enables the swinging upright arm 122 to be forced to the left to place the recessed shoulder 123 beneath the pin 124 carried on the arm 125 of the rock-lever 106 which actuates the inker throw-off. The lowering of the bell-crank lever 112 also simultaneously brings the cam-roller 138 into the path of the inker throw-off cam 139 when the high part of this cam engages the cam-roller 138 to force upwardly the bell-crank lever 112 which immediately throws off the inking rolls 91 from the form-cylinder 9 as shown in Fig. 5. The latch-pin 117 at the same time re-engages the notch 116 upon the upward movement of the bell-crank lever 112 to hold the lever arm 114 in its raised position after the cam-roller 138 rides off the high part of the cam 139. The arm 122 is moved to the dotted line position shown in Fig. 5 by hand to allow the pin 124 to pass below the shoulder 123 as shown in Fig. 1, when the inking rolls 91 are restored by the hand lever 111 to operative position in contact with the form-cylinder 9. The latch 70 is reset on the shaft 63 when the latter is rotated in an anti-clockwise direction by the hand-lever 69 which allows the bracket 41 to swing to the left to bring the rod-end 49 into position to engage the shoulder 56 to automatically throw-on the impression when the cam 32 revolves so as to force the rod-end 49 down on the shoulder 56 to break the toggle levers 25 and 26 which movement restores the parts 100 to the position shown in Fig. 1. By this construction I have devised two automatic sequential throw-offs for the impression and inking mechanisms, both positively actuated by cams inter-adjustably set on the non-shiftable impression-cylinder shaft through continued movement of the press, the inker throw-off being controlled, but not operated, by the impression-throw-off, with the timing of such inker-throw-off being set in any predetermined sequence in the cycle with relation to the impression throw-off and without altering or shifting any part of the impression throw-off mechanism.

In the modified embodiment of my invention shown in Figs. 6 and 7, I employ the same devices for throwing off the impression and for raising the inking rolls from the form or plate-cylinder as has been heretofore shown and described in the embodiment 125 130

shown in Figs. 1, 2, 3, 4 and 5. In this modification I have combined with the automatic trip devices controlled by the stock for the two sequential throw-offs manual means for setting the inker throw-off mechanisms which will thereafter act to throw-off the ink rolls at a predetermined point in the continued movement of the press. The stub shaft 67 loosely carries the hand lever 140 operating the rock-arm 141 to which the curved arm 142 is pivotally secured. At the extremity of the arm 142 is the hook 143 adapted to engage with the stud 144 on the arm 137. The arm 142 inside the hook 143 has the cam-face 145 formed on its under side which is adapted to ride on the stud 146 secured to the frame 8. When the hand-lever 140 is lifted it swings the arm 141 to the right thereby also moving the arm 142 laterally to the right. This transverse movement of the arm 142 swings the cam-roller 138 into position to be acted on by the cam 139; and as the arm 142 moves to the right it rides slightly upward on the stud 146 and thus frees the stud 144 from the hook 143 as shown in Fig. 7, so that the arm 137 is in position to be acted on by the cam 139 without affecting the position of the trip-shaft 63. By this construction the operator 25 may manually set the inker throw-off mechanism so that the inking rolls 91 may be thereafter thrown off by power without tripping the feeder or throwing off the cylinders all during the continued movement of the press.

In both forms of construction the two actuating cams 32 and 139 are preferably arranged interadjustably on the impression-cylinder shaft 14 yet they may be located 40 and set upon other operative parts of the press so as to insure the positive predetermined sequence of operation desired, so long as they are disposed upon some non-shiftable member in the press where other devices are brought into their respective paths, the operation of the cams on such devices being occasioned through the continued movement 45 of the press.

I claim as my invention:

50 1. In a printing-press having two members constituting a printing couple, an inking mechanism therefor with means for throwing off same normally held inoperative by a latch, means for throwing off the impression, and means carried by said impression throw-off means to directly disengage the latch and simultaneously bring the inker throw-off means into position for operation after the impression is thrown off.

60 2. In a printing-press having two members constituting a printing couple, an inking mechanism therefor with means for throwing off same normally held inoperative by a latch, means for throwing off the impression, and means carried by said impres-

sion throw-off means to directly disengage the latch and simultaneously bring the inker throw-off means into position for operation at a predetermined point in the cycle after the impression is thrown off.

70

3. In a printing-press having two members constituting a printing couple, an inking mechanism therefor with means for throwing off same normally held inoperative by a latch, means for throwing off the impression, and means carried by said impression throw-off means to directly disengage the latch and simultaneously bring the inker throw-off means into position for operation after the impression is thrown off operable through the continued movement of the press.

75

4. In a printing-press having two members constituting a printing couple, an inking mechanism therefor with means for throwing off same normally held inoperative by a latch, means for throwing off the impression, and means carried by said impression throw-off means to directly disengage the latch and simultaneously bring the inker throw-off means into position for operation at a predetermined point in the cycle after the impression is thrown off operable through the continued movement of the press.

80

5. In a printing-press having two members constituting a printing-couple, an inking mechanism therefor, means for throwing off said inking mechanism, means for throwing off the impression between said members having a releasable connection with the inker throw-off to directly bring the latter into operative position after the impression is thrown off, and means operable through the continued movement of the press to actuate said inker throw-off after said connection has been released.

90

6. In a printing-press having two members constituting a printing-couple, an inking mechanism therefor, means for throwing off said inking mechanism, means for throwing off the impression between said members having a releasable connection with the inker throw-off to directly and simultaneously bring the latter into operative position after the impression is thrown off, and means operable through the continued movement of the press to actuate said inker throw-off after said connection has been released.

100

7. In a printing-press having two members constituting a printing-couple, an inking mechanism therefor, means for throwing off said inking mechanism, means for throwing off the impression between said members having a releasable connection with the inker throw-off to directly bring the latter into operative position after the impression is thrown off, and means operable through the continued movement of the press to actuate at a predetermined point in the cycle

105

110

115

120

125

130

said inker throw-off after said connection has been released.

8. In a printing-press having two members constituting a printing-couple, an inking mechanism therefor, means for throwing off said inking mechanism, means for throwing off the impression between said members having a releasable connection with the inker throw-off to directly and simultaneously bring the latter into operative position after the impression is thrown off, and means operable through the continued movement of the press to actuate at a predetermined point in the cycle said inker throw-off after said connection has been released.

9. In a printing-press having two members constituting a printing couple, an inking mechanism therefor with means for throwing off the same normally held inoperative by a latch, means for throwing off the impression having a connection with the inker throw-off to simultaneously and directly disengage the latch and bring the inker-throw off means into position for operation, and separate means operable through the continued movement of the press to sequentially actuate the impression and inker throw-offs.

10. In a printing-press having two members constituting a printing couple, an inking mechanism therefor with means for throwing off same, normally held inoperative by a latch, means for throwing off the impression having a connection with the inker throw-off to simultaneously and directly disengage the latch and bring the inker-throw off means into position for operation, and separate means operable through the continued movement of the press to sequentially actuate the impression and inker throw-offs at predetermined points in the cycle.

11. In a printing-press having two or more coacting members, an inking mechanism therefor with means to throw-off same, means for separating two of said coacting members to throw off the impression, means directly actuated by said impression throw-off means to set the inker throw-off into position for operation, separate means for actuating said inker throw-off after the impression is thrown off, both said throw-off means being inter-adjustable to cause a positive predetermined sequence of operation in said throw-offs.

12. In a printing-press having two or more coacting members, an inking mechanism therefor with means to throw-off same, means for separating two of said coacting members to throw off the impression, means directly actuated by said impression throw-off means to set the inker throw-off into position for operation, separate means for actuating said inker throw-off at a predetermined point in the cycle after the im-

pression is thrown off, both said throw-off means being inter-adjustable to cause a positive predetermined sequence of operation in said throw-offs.

13. In a printing-press having two or more coacting members, an inking mechanism therefor with means to throw-off same, means for separating two of said coacting members to throw off the impression, means directly actuated by said impression throw-off means to set the inker throw-off into position for operation, separate means for actuating said inker throw-off after the impression is thrown off, both said throw-offs being actuated by the continued movement of the press, both said throw-off means being inter-adjustable to cause a positive predetermined sequence of operation in said throw-offs.

14. In a printing-press having two or more coacting members, an inking mechanism therefor with means to throw-off same, means for separating two of said coacting members to throw off the impression, means directly actuated by said impression throw-off means to set the inker throw-off into position for operation, separate means for actuating said inker throw-off at a predetermined point in the cycle after the impression is thrown off, both said throw-offs being actuated by the continued movement of the press, both said throw-off means being inter-adjustable to cause a positive predetermined sequence of operation in said throw-offs.

15. In a printing-press having a plurality of printing members, an inking mechanism therefor, means for throwing off said inking mechanism normally held inoperative, means for separating two of said printing members to throw off the impression, a direct connection between said impression throw-off means and said inker throw-off to place the latter in operative position, and means actuated by the continued movement of the press to thereafter actuate the inker throw off independently of said direct connection with the impression throw-off means.

16. In a printing-press having a plurality of printing members, an inking mechanism therefor, means for throwing off said inking mechanism normally held inoperative, means for separating two of said printing members to throw off the impression, a direct connection between said impression throw-off means and said inker throw-off to simultaneously place the latter in operative position, and means actuated by the continued movement of the press to thereafter actuate the inker throw-off independently of said direct connection with the impression throw-off means.

17. In a printing-press having a plurality of printing members, an inking mechanism therefor, means for throwing off said inking

- mechanism normally held inoperative, means for separating two of said printing members to throw-off the impression, a direct connection between said impression throw-off means and said inker throw-off to place the latter in operative position, and means actuated by the continued movement of the press to thereafter actuate the inker throw-off independently of said direct connection with the impression throw-off means but in predetermined sequence thereto.
18. In a printing-press having a plurality of printing members, inking mechanism therefor, means for throwing off said inking mechanism normally held inoperative, means for separating two of said printing members to throw off the impression and simultaneously and directly bring said inker throw-off means in operative position, means to actuate said inker throw-off, both said throw-offs dependent upon the continued operation of the press, and both being inter-adjustably timed to cause a positive predetermined sequence of operation in said throw-offs.
19. In a printing-press having a plurality of printing members, inking mechanism therefor, means for throwing-off said inking mechanism normally held inoperative, means for separating two of said printing members to throw off the impression and simultaneously and directly bring said inker throw-off means in operative position, means to actuate said inker throw-off, both said throw-offs occurring in sequence, and dependent upon the continued operation of the press, and both being inter-adjustably timed to cause a positive predetermined sequence of operation in said throw-offs.
20. In a printing-press having a plurality of printing members, inking mechanism therefor means for throwing off said inking mechanism normally held inoperative, means for separating two of said printing members to throw-off the impression and simultaneously and directly bring said inker throw-off means in operative position, means to actuate said inker throw-off, both said throw-offs occurring in sequence at predetermined points in the cycle, and dependent upon the continued operation of the press, and both being inter-adjustably timed to cause a positive predetermined sequence of operation in said throw-offs.
21. In a printing-press having a form-cylinder, a transfer-cylinder and an impression-cylinder, inking mechanism for the form-cylinder including means to throw-off same normally held inoperative, means for separating the transfer-cylinder from both the other cylinders to throw off the impression and simultaneously and directly bring the inker throw-off in operative position, and a separate cam mechanism mounted on, and operable through the continued movement of the impression-cylinder to actuate the inker throw-off after and independently of the impression-throw-off.
22. In a printing-press having a form-cylinder, a transfer-cylinder and an impression-cylinder, inking mechanism for the form-cylinder including means to throw off same normally held inoperative, means for separating the transfer-cylinder from both the other cylinders to throw off the impression and simultaneously and directly bring the inker throw-off in operative position, and a separate cam mechanism mounted on, and operable through the continued movement of the impression-cylinder to actuate the inker throw-off after and independently of the impression-throw-off.
23. In a printing-press having a form cylinder, a transfer-cylinder and an impression-cylinder, inking mechanism for the form-cylinder including means to throw off same, means for separating the transfer-cylinder from both the other cylinders to throw off the impression and simultaneously and directly bring the inker throw-off in operative position, and a separate cam mechanism mounted on, and operable through the continued movement of the press to actuate the inker throw-off at a predetermined point in the cycle after and independently of the impression throw-off.
24. In a printing-press having a form-cylinder, a transfer-cylinder and an impression-cylinder, inking mechanism for the form-cylinder including means to throw-off same, means for separating the transfer-cylinder from both the other cylinders to throw off the impression and simultaneously and directly bring the inker throw-off in operative position, and a separate cam mechanism mounted on, and operable through the continued movement of the impression-cylinder to actuate the inker throw-off after and independently of the impression throw-off.
25. In a printing-press having a form-cylinder, a transfer-cylinder and an impression-cylinder, inking mechanism for the form-cylinder including means to throw-off same, means for separating the transfer-cylinder from both the other cylinders to throw off the impression and simultaneously and directly bring the inker throw-off in operative position, and a separate cam mechanism mounted on, and operable through the continued movement of the impression-cylinder to actuate the inker throw-off after and independently of the impression throw-off.
26. In a printing-press having a form-cylinder, a transfer-cylinder and an impression cylinder, inking mechanism for the form-cylinder including means to throw-off same, means for separating the transfer-cylinder from both the other cylinders to throw off the impression and simultaneously and directly bring the inker throw-off in operative

position, and a separate cam mechanism mounted on, and operable through the continued movement of the impression-cylinder to actuate the inker throw-off at a predetermined point in the cycle after and independently of the impression throw-off.

27. In a printing-press having a form-cylinder, a transfer-cylinder and an impression-cylinder, inking mechanism for the form-cylinder including means to throw off same normally held inoperative, means to throw off said transfer-cylinder from both the other cylinders and simultaneously and directly bring said inker throw-off in operative position, both actuated by the rotation of the impression-cylinder, and a cam carried by the impression-cylinder and operable by its continued movement to actuate said inker throw-off independently of the impression throw-off.

28. In a printing-press having a form cylinder, a transfer-cylinder and an impression-cylinder, inking mechanism for the form-cylinder including means to throw off same normally held inoperative, means to throw off said transfer-cylinder from both the other cylinders and simultaneously and directly set said inker throw-off in operative position, both actuated by the rotation of the impression-cylinder, and a cam carried by the impression-cylinder and operable by its continued movement to actuate said inker throw-off independently of the impression throw-off.

29. In a printing-press having a form-cylinder, a transfer-cylinder and an impression-cylinder, inking mechanism for the form-cylinder including means to throw off same normally held inoperative, means to throw off said transfer-cylinder from both the other cylinders and simultaneously and directly set said inker throw-off in operative position, both actuated by the rotation of the impression-cylinder, and a cam carried by the impression-cylinder and operable by its continued movement to actuate said inker throw-off at a predetermined point in the cycle independently of the impression throw-off.

30. In a printing-press having a form-cylinder, a transfer-cylinder and an impression-cylinder, inking mechanism for the form-cylinder including means to throw off same normally held inoperative, means including a part carried by said impression-cylinder to throw off said transfer-cylinder from both the other cylinders and simultaneously and directly bring said inker throw-off in operative position, both actuated by the rotation of the impression-cylinder, and a separate part carried by the impression-cylinder and operable by its continued movement to actuate said inker throw-off independently of the impression throw-off.

31. In a printing-press having a form-cyl-

inder, a transfer-cylinder and an impression-cylinder, inking mechanism for the form-cylinder including means to throw-off same normally held inoperative, means including a part carried by said impression-cylinder to throw off said transfer-cylinder from both the other cylinders and simultaneously and directly set said inker throw-off in operative position, both actuated by the rotation of the impression-cylinder, and a separate part carried by the impression-cylinder and operable by its continued movement to actuate said inker throw-off independently of the impression throw-off.

32. In a printing-press having a form cylinder, a transfer-cylinder and an impression-cylinder, inking mechanism for the form-cylinder including means to throw-off same normally held inoperative, means including a rotatable cam carried by said impression-cylinder to throw off said transfer-cylinder from both the other cylinders and simultaneously and directly bring said inker throw-off in operative position, both actuated by the rotation of the impression-cylinder, and a separate rotatable cam also carried by the impression-cylinder and operable by its continued movement to actuate said inker throw-off independently of the impression throw-off.

33. In a printing-press having a form-cylinder, a transfer-cylinder and an impression-cylinder, inking mechanism for the form-cylinder including means to throw-off same normally held inoperative, means including a rotatable cam carried by said impression-cylinder to throw off said transfer-cylinder from both the other cylinders and simultaneously and directly set said inker throw-off in operative position, both actuated by rotation of the impression-cylinder, and a separate rotatable cam also carried by the impression-cylinder and operable by its continued movement to actuate said inker throw-off independently of the impression throw-off.

34. In a printing-press having a plurality of printing members, an inking mechanism therefor, normally inoperative means to throw off the inking mechanism, means to throw off impression, a member movable to bring said inker throw-off means into operative position and also release said member during its movement, and means for actuating said inker throw-off means, after said member has been released, operable through the continued movement of the press without operating said impression throw-off.

35. In a printing-press having a plurality of printing members, an inking mechanism therefor, normally inoperative means to throw off impression, a manual member movable to bring said inker throw-off means into operative position and also release said member during its movement, and means for

5 tuating said inker throw-off means, after said member has been released, operable through the continued movement of the press without operating said impression throw-off.

10 36. In a printing-press having a plurality of printing members, an inking mechanism therefor, normally inoperative means to throw off the inking mechanism, means to throw off impression, a member movable to bring said inker throw-off means into operative position and also release said member during its movement, and means for actuating said inker throw-off means, after said 15 member has been released at a predetermined point in the cycle, operable through the continued movement of the press without operating said impression throw-off.

20 37. In a printing-press having a plurality of printing members, an inking mechanism therefor, normally inoperative means to throw off the inking mechanism, means to throw off impression, a manually controlled member movable to bring said inker throw-off means into operative position and also release said member during its movement, and separate means for actuating said inker 25 throw-off means, after said member has been released, operable through the continued 30 movement of the press without operating said impression throw-off.

35 38. In a printing-press having a plurality of printing members, an inking mechanism therefor, normally inoperative means to throw off the inking mechanism, means to throw off impression, a manually controlled member movable to bring said inker throw-off means into operative position and also release said member during its movement, 40 and separate means for actuating said inker throw-off, after said member has been released at a predetermined point in the cycle, operable through the continued movement of the press without operating said impression 45 throw-off.

50 39. In a printing-press having a form-cylinder, a transfer-cylinder and an impression-cylinder, inking mechanism for the form-cylinder including means to throw-off same normally held inoperative, means to throw off said transfer-cylinder from both the other cylinders, manually controlled means for setting said inker throw-off means in operative position, and means carried by 55 the impression-cylinder and operable by its continued movement to actuate said inker throw-off without operating said means for throwing off the transfer-cylinder.

60 40. In a printing-press having a form-cylinder, a transfer-cylinder and an impression-cylinder, inking mechanism for the form-cylinder including means to throw-off same normally held inoperative, means to throw off said transfer-cylinder from both 65 the other cylinders, manually controlled

means for setting said inker throw-off means in operative position, and means carried by the impression-cylinder and operable by its continued movement to actuate said inker throw-off at a predetermined point in the 70 cycle without operating said means for throwing off the transfer-cylinder.

75 41. In a printing-press having two members constituting a printing couple, an inking mechanism therefor including means for throwing off same, means for throwing off the impression controlled by the stock having a connection with the inker throw-off to set the latter for operation after the impression is thrown off, and means to break said connection as the inker throw-off is set.

80 42. In a printing-press having two members constituting a printing couple, an inking mechanism therefor including means to throw off same normally held inoperative, 85 means to throw-off impression, means controlled by the stock to directly bring said inker throw-off in operative position, and separate mechanical means to thereafter actuate said inker throw-off through the continued movement of the press without operating said impression throw-off.

90 43. In a printing-press having two members constituting a printing couple, an inking mechanism therefor including means to throw off same normally held inoperative, 95 means to throw-off impression, means controlled by the stock to directly bring said inker throw-off in operative position, and separate mechanical means to thereafter actuate said inker throw-off through the continued movement of the press at a predetermined point in the cycle without operating said impression throw-off.

100 44. In a printing-press having a plurality of printing members, inking mechanism therefor including means for throwing off same normally held inoperative, means controlled by the stock for separating two of said members to throw off the impression 105 having a connection with the inker throw-off to move said inker throw-off in operative position while automatically breaking such connection when said inker throw-off is in operative position, and means to actuate said 110 inker throw-off operable in the continued movement of the press.

115 45. In a printing-press having a plurality of printing members, inking mechanism therefor including means for throwing off same normally held inoperative, 120 means controlled by the stock for separating two of said members to throw off the impression having a connection with the inker throw-off to move said inker throw-off in operative position while automatically breaking such connection when said inker throw-off is in operative position, and means to actuate said inker throw-off operable in the continued 125 movement of the press and in predetermined 130

sequence to the operation of the impression throw-off.

46. In a printing-press having a plurality of printing members, inking mechanism therefor including means for throwing off same normally held inoperative by a latch, means for separating two of said members to throw-off the impression having a connection with the inker throw-off to release the latch and move said inker-throw off in operative position and break such connection, and means to actuate said inker throw-off in predetermined sequence to the impression throw-off.

47. In a printing-press having a plurality of printing members, inking mechanism therefor including means for throwing off same normally held inoperative by a latch, means for separating two of said members to throw-off the impression having a connection with the inker throw-off to release the latch and move said inker-throw off in operative position and simultaneously break such connection, and means to actuate said inker throw-off in predetermined sequence to the impression throw-off.

48. In a printing-press having a plurality of printing members, inking mechanism therefor including means for throwing off same normally held inoperative by a latch, means for separating two of said members to throw-off the impression having a connection with the inker throw-off to release the latch and move said inker-throw off in operative position and simultaneously break such connection, and means to actuate said inker throw-off in predetermined sequence to the impression throw-off, and means for varying the timed relation between said throw-offs.

49. In a printing-press having a plurality of printing members, inking mechanism therefor including means for throwing off same normally held inoperative by a latch, means for separating two of said members to throw-off the impression having a connection with the inker throw-off to release the latch and move said inker-throw off into operative position and simultaneously break such connection, means to actuate said inker throw-off in predetermined sequence to the impression throw-off, and means for varying the timed relation between said throw-offs.

50. In a printing-press having a plurality of printing members, inking mechanism therefor including means for throwing off same normally held inoperative by a latch, means for separating two of said members to throw-off the impression having a connection with the inker throw-off to release the latch and move said inker throw-off in operative position and simultaneously break such connection, and means to actuate said inker throw-off in predetermined sequence to the impression throw-off but independently thereof.

51. In a printing-press having a plurality of printing members, inking mechanism therefor including means for throwing off same normally held inoperative by a latch, means for separating two of said members to throw-off the impression having a connection with the inker throw-off to release the latch and move said inker-throw off into operative position while breaking said connection, and means to actuate said inker throw-off in predetermined sequence to the impression throw-off while resetting said latch.

52. In a printing-press having a plurality of printing members, inking mechanism therefor including means for throwing off same normally held inoperative by a latch, means for separating two of said members to throw-off the impression having a connection with the inker throw-off to release the latch and move said inker-throw-off into operative position while breaking said connection, and a single means to actuate said inker throw-off in predetermined sequence to the impression throw-off while resetting said latch.

53. In a printing-press having a plurality of printing members, inking mechanism therefor including means for throwing off same normally held inoperative by a latch, means for separating two of said members to throw-off the impression having a connection with the inker throw-off to release the latch and move said inker-throw-off into operative position while breaking said connection, and a single means to actuate said inker throw-off in predetermined sequence to the impression throw-off while simultaneously resetting said latch.

CHARLES W. HARROLD.
